William Abrams INVENTOR.

UNITED STATES PATENT OFFICE.

**WILLIAM ABRAMS, OF CHICAGO, ILLINOIS, ASSIGNOR TO THE MEYERCORD COMPANY,
OF CHICAGO, ILLINOIS.**

DESIGN FOR A PLATE OR SIMILAR ARTICLE OF MANUFACTURE.

48,463.

Specification for Design.

Patented Jan. 18, 1916.

Application filed October 11, 1915. Serial No. 55,358. Term of patent 3½ years.

To all whom it may concern:

Be it known that I, WILLIAM ABRAMS, a citizen of the United States, residing at Chicago, in the county of Cook, State of Illinois, have invented a new, original, and ornamental Design for Plates or Similar Articles of Manufacture, of which the following is a specification, reference being had to the accompanying drawing, forming a part thereof.

The figure is a plan view of a plate illustrating my new design.

I claim:

The ornamental design for a plate or similar article of manufacture as shown.

WILLIAM ABRAMS.

Witnesses:

J. CROMPTON,
C. JAROS.
